Attorney

UNITED STATES PATENT OFFICE

EDWARD J. GULICK, OF ELKHART, INDIANA, ASSIGNOR TO C. G. CONN, LTD., OF ELKHART, INDIANA, A CORPORATION OF INDIANA

SAXOPHONE KEY PAD

Application filed October 6, 1930. Serial No. 486,699.

My invention relates to wind musical instruments, and especially to key pads for saxophones, and the like.

The key pad now in common use on saxophones and like instruments comprises a body made of felt and a cover therefor usually made of kid leather. Both of these elements absorb moisture from the instrument interior and deterioration of the pad unit begins early on that account. The kid leather cover absorbs moisture and dries out when the instrument is not in use, and the alternate moistening and drying of the pad cover causes hardening and distortion thereof, and thereby an imperfect or leaky contact of the pad with the tone opening flange, or seat, on the instrument body results. Therefore, to insure the production of the best tones the key pad must be frequently renewed.

20 An object of my invention is to provide a key pad which is impervious to moisture.

Another object of the invention is to provide a key pad which has a moisture proof facing or cover.

25 A third object of the invention is to provide a moisture proof key pad which is composed of the same number of parts as the conventional type of absorbent pad.

Still another object of the invention is to 30 provide a key pad having a cover or facing which is both moisture proof and impression retaining.

Another object of the invention is to provide a key pad having a metallic foil cover or facing which is substituted for the usual kid leather cover to exclude moisture from the felt pad body and to produce a permanent impression in the cover or facing when the key pad is pressed into engagement with the tone opening flange of the instrument.

35 Other and more specific objects of the invention are mentioned herein.

The preferred embodiment of my invention is illustrated in the accompanying drawings, wherein

Figure 1 illustrates the tone opening socket or flange of a saxophone body to which my improved key-pad is applied;

Fig. 2 illustrates a perspective of the pad body and cover secured thereabout;

Fig. 3 illustrates a perspective of the pad body and the cover or facing secured thereto but unfinished;

Fig. 4 illustrates a modified form of the invention;

Fig. 5 illustrates another modification of the invention;

Fig. 6 illustrates still another modification thereof; and

Fig. 7 illustrates the application of the pad cover or facing to the pad body by stitching.

Similar numerals of reference indicate like parts throughout the several views on the drawings.

Referring now to the details of the drawings the numeral 1 indicates a fragment of a tubular saxophone body, in cross-section, which is provided with the usual tone opening 2 which is encompassed by the usual annular flange 3 upon which the key-pad 4 is adapted to seat. The pad 4 is removably mounted in a pad-cup or carrier 5 which is rigidly connected with the key-arm 6 which may be tiltably mounted in the instrument at 7, as is well known in the art.

The key-pad 4, as illustrated in Figures 1, 2 and 3 of the drawings, comprises the annular felt pad body 8 and the metallic foil cover or facing 9, the latter being substantially larger in diameter than the body 8, the outer periphery 10 thereof being folded over the pad-body edge and secured about the pad body back by adhesive, or otherwise in any suitable manner. The cover or facing 9 may be centrally stitched to the pad body 8 at 11 to prevent sagging of the former in the larger sizes of pads.

A key-pad thus constructed makes a most effective and durable article, for the metallic foil cover or facing 9 not only effectually excludes moisture from the felt pad body 8, but also said cover or facing readily receives and retains a permanent annular impression 12 by pressure contact with the tone opening flange 3, whereby a perfect seal is made between said cover or facing and the tone opening flange, thereby producing the maximum quality of tone. Moreover, the cover or facing 9, being metallic, will not shrink, expand or warp, and is sufficiently tough and tena-

cious to readily withstand the use to which it may be subjected without tearing or puncturing. The durability of this key-pad is therefore much greater than the common type of pad, and much more efficient at all times.

The modifications illustrated in Figures 4 and 5 include the felt pad body 8 and the metallic foil cover 9, also a retaining ring 13 which encompasses the pad body 8, and which is frictionally retained within the pad-cup 5, said ring being provided with the outwardly extending annular flange 14 which engages the lower edge of the pad-cup 5 to facilitate the mounting of the pad unit within said cup.

In Fig. 4 the metallic foil cover or facing 9 is shown fully covering both pad-body 8 and the flanged ring 13, and in Fig. 5 the foil 20 cover 9 encloses only the lower face of the 25 pad body 8 and the flange 14 of the ring 13, said foil having its outer periphery gripped between the pad-cup and said ring flange. In Fig. 6 the pad unit includes a fabric or 30 cloth insert 15 which is secured about the pad body 8 between the metallic foil cover 9 and said pad body, this unit being similar in other respects to the pad unit illustrated and described in Figures 1, 2 and 3.

30 I claim:—

1. The combination with the flanged tone opening of a wind musical instrument of the character described, of a tilttable pad carrier mounted adjacent said tone opening, a yieldable pad body mounted upon said pad carrier, and a facing member for said pad body, said facing member being made of non-absorbent, permanent impression retaining material and actuated into direct engagement 40 with said tone opening flange upon actuation of said pad carrier.

2. A key-pad for a wind musical instrument provided with a flanged tone opening comprising, a yieldable pad body, and a facing member for said pad body, said facing member being made of non-absorbent, permanent impression retaining material adapted to be brought into direct contact with said tone opening flange.

3. The combination with the flanged tone opening of a wind musical instrument of the character described, of a tilttable pad carrier mounted adjacent said tone opening, a yieldable pad body mounted upon said pad carrier, and a cover for said pad body, said cover being made of non-absorbent, permanent impression retaining material and folded over the edge of the pad body and upon the back thereof.

4. A key-pad for a wind musical instrument provided with a flanged tone opening comprising, a yieldable pad body, and a cover for said pad body, said cover being made of non-absorbent, permanent impression retaining material folded over the pad body edge

upon the back thereof and adapted to be brought into direct contact with said tone opening flange.

5. The combination with the flanged tone opening of a wind musical instrument of the character described, of a tilttable pad carrier mounted adjacent said tone opening, a yieldable pad body mounted upon said pad carrier, and a metallic foil facing member for said pad body and secured thereto, said facing member being actuated into direct engagement with said tone opening flange upon actuation of said pad carrier.

6. A key-pad for a wind musical instrument provided with a flanged tone opening comprising, a yieldable pad body, and a metallic foil facing member secured to said pad body and adapted to be brought into direct engagement with said tone opening flange.

7. In a key-pad for a wind musical instrument provided with a flanged tone opening, a yieldable pad body, a flanged retaining ring encompassing said pad body, and a metallic foil cover for said pad body and retaining ring and adapted for direct contact with said tone opening.

8. In a key-pad for a wind musical instrument provided with a flanged tone opening, a yieldable pad body, a flanged retaining ring encompassing said pad body, and a metallic foil cover for said pad body and retaining ring, said cover being folded about said retaining ring upon the back of said pad body and adapted for direct engagement with said tone opening flange.

EDWARD J. GULICK.
